PADLOCK

John Hines, South Norwalk, Conn., assignor to
 Norwalk Lock Company, New York, N. Y., a
 corporation of Connecticut

Application February 14, 1945, Serial No. 577,858

12 Claims. (Cl. 70—38)

1

The present invention relates to locks and specifically is concerned with a novel padlock wherein a tumbler carrying and key controlled plug is utilized to operate bolt means for unlocking the latter from a conveniently accessible shackle. The primary object of the invention resides in the provision of a simplified padlock having relatively few parts to assemble and embodying offset and pivoted bolts adapted to be actuated upon rotation of the plug to withdraw the locking portions of the bolts simultaneously from the spaced legs of the slidably and rotatably guided shackle. The invention has as a further object provision of a hollow casing having a rearwardly arranged bearing integral with spaced sockets disposed within the casing and having a hollow boss integrally merged with one of the sockets and within the body of the casing, the arrangement being such that spaced fulcrum pins for pivotally sustaining the bolts are removably mounted in the sockets while one of the fulcrum pins traverses the hollow boss to characterize stop means to preclude the complete withdrawal of the shackle which is spring controlled and automatically shiftable outwardly upon the disengagement of the bolts from the legs thereof. Further functional and structural features of the invention will appear from the following detailed specification considered with the accompanying drawings wherein:

Fig. 1 is a rear elevational view of the padlock with the cover thereof removed to illustrate the internal mechanism.

Fig. 2 is a transverse sectional view of Fig. 1, and

Fig. 3 is an exploded view of the padlock.

According to the invention the padlock P embodies a casing C that is preferably die cast and is provided with a tubular concentrically arranged bearing B integrally merged with the front wall 10 of the casing.

Rotatably mounted within and guided by bearing B is the key receiving cylindrical plug 11 having the conventional slidably guided spring controlled plate tumblers 12 adapted to be received in a slot as 13 interrupting the bearing to removably interlock therewith.

With the key K arranged in the plug, tumblers 12 are out of slot 13 and flush with the outer surface of the cylindrical body of the plug and hence the latter may be rotated by the key.

Integral with and laterally extending from the bearing B are the spaced sockets 14 closely and removably receiving fulcrum pins 15 normally

adapted to project a small distance out of the pin positioning sockets 14.

Disposed laterally of bearing B but merged with one of the sockets 14 and integral therewith and bearing B is the boss 17 having the vertical bore 18 for slidably and rotatably guiding the long leg 19 of the U-shaped shackle 20.

The bore 18 of boss 17 is normal to the bore or opening 21 in the adjacent bearing 14 and intersects or communicates therewith to permit its removably associated pin or post 15 inserted in opening 21 to partly extend into and overhang bore 18 and form a stop to coact with collar 22 of the leg 19 having the flattened face 23 to permit access to the flange 22 and including a notched or keeper portion 24.

Removably and pivotally sustained by the removable pins 15 are the opposed locking jaws 25 provided with lower limbs 26 having the straight faces 27. These jaws also include openings 28 closely but removably receiving fulcrum pins 15 to define a pivotal connection.

The upper limbs of the jaws embody the inclined intermediate portions 29 which extend in a forwardly direction towards bearing B and overhang the latter below the top wall 30 of the casing and the terminals of the upper limbs each embody a lateral extending cam shaped lip 31 for disengageably interlocking with the keeper portions or notches 24 and 32 of the long and short legs 19 and 33 of the shackle respectively.

The lower limbs 26 of the jaws are arranged in the spaced slots 34 at the rear end of the plug and are adapted to be spread apart or actuated when the rectilinear faces 27 are operated by the rectilinear faces 35 of the opposed slots 34 upon rotation of the plug.

Lugs 37 extending from the intermediate portions of the jaws or levers 25 removably hold the helicoidal spring 36 which tends to urge the upper terminals of the jaws apart and the lower limbs 26 interlocked with the walls of slots 34, the lower terminals awaiting to be actuated by the web or restricted portion 35' also having the straight faces 35 straddled by the lower limbs.

The annular rim 37' of the casing is interrupted by a cutaway portion or recess 38 for receiving a complementary closure lip 39 removably and closely fitting into recess 38 and integral with the cover 40 having a substantially annular inside raised boss 41 seated against projection 42 extending from bearing B and against the fulcrum pins 15, thus desirably sustaining the latter in sockets 14 and concomitantly properly positioning the cover relative to the casing after

which the latter has its beveled rim 37' spun over at 43 to hold the cover in its set position.

Extending from and integral with the casing are the hollow nipples 44 and 45, the former together with boss 17 rotatably and slidably guiding the leg 19 of the shackle while the latter removably and rectilinearly guides the displacement of the short leg 33.

Confined within the bore 18 of the hollow boss 17 is the helicoidal spring 46 and collar 22 is seated on this spring and hence the shackle is resiliently seated and is automatically projected in a direction away from the casing upon the disengagement of the lips 31 from the notches 24 and 32.

With the present invention no rivets, screws or similar fastening means need be utilized. Moreover the padlock comprises relatively few simple parts adapted for quick assembly or replacement.

With the cover 40 in its closed relation with the casing, the fulcrum pins are against boss 41 of the cover and if the key be inserted in the plug, the tumblers 12 are withdrawn from slot 13 in the bearing. Hence, the plug may be rotated clockwise or counterclockwise. In either case, walls 35 of slots 34 of the plug shift the lower limbs of the jaws outwardly as indicated by the dash and dot lines in Fig. 1 while the offset upper limbs of the jaws swing towards each other against the resistance of the normally expanded spring 36. Thus lips 31 are removed from the legs of the shackle and the latter is projected outwardly by the formerly compressed spring 46 until collar 22 strikes the fulcrum pin 15 overhanging bore 18 of the boss 17. By such action the short leg 32 is completely withdrawn from the nipple 45 and the shackle may then be rotated relative to the nipple 44.

For again interlocking the shackle with the bolt, the former is rotated to aline leg 33 with the nipple 45 and the shackle is depressed against the spring 46 and with the plug in its neutral position lips 31 of the bolts interlock with the keepers 24 and 32 and such action is maintained by the spring 36.

The simplicity in the matter of assembling is apparent. To this end, spring 46 is first inserted in the bore 18. Thereafter leg 19 is positioned in the nipple 44 and depressed. The plug is then positioned in the bearing B. The fulcrum pins are now inserted in the sockets 14 leaving predetermined portions thereof projecting from the bearings. Thereafter the opposed bolts are mounted on the fulcrum pins and interlocked with the plug. Spring 36 is then arranged on the projections 37. Following this, the cover is disposed within the rim 37' and against the inner annular but interrupted shoulder 47 and the projecting lug 42 of the bearing B. By such positioning of the cover 40, the rearwardly inclining lip 39 thereof is received in the complementary gap 38 and becomes seated against the shoulder 48 and under the arcuate and overhanging ledge or margin 49 of the top wall 30 integrally merged with and interconnecting the spaced nipples 44 and 45 after which the beveled rim 37' is spun over as at 43 to firmly anchor the cover in place and pursuant to the positioning of the cover, the terminal portion 50 of the plug is rotatably received in the centrally arranged recess 51 of the cover or closure.

Various changes may be made in detail of construction and arrangement of parts without

departing from the spirit of the invention or sacrificing any of the advantages therein.

I claim:

1. In a padlock, a hollow casing having a bearing, a hollow boss within said casing and integral therewith, key controlled means rotatably guided by said bearing and having tumbler means for removably interlocking with said bearing, socket means interrupting said boss and communicating therewith, a pair of spaced nipples extending from said casing, a shackle having a relatively short leg slidably guided by one of said nipples and having a relatively long leg rotatably and slidably guided by the other nipple of said pair, pin means at least in part disposed in said socket means and said boss, bolt means pivotally mounted on said pin means and having means actuated by said key controlled means, said legs having keeper means, and means extending from said bolt means for interlocking with said keeper means.
2. In a padlock, a hollow casing having a bearing, a boss within said casing and integral therewith and having a bore, key controlled means rotatably guided by said bearing and having tumbler means for removably interlocking with said bearing, socket means having an opening and communicating with said bore, a pair of spaced and hollow nipples extending from said casing and communicating with said bore and the interior of said casing, a shackle having a relatively short leg slidably guided by one of said nipples and having a relatively long leg rotatably and slidably guided by the other nipple of said pair, pin means at least in part disposed in said opening and in part projecting into said bore, bolt means pivotally mounted on said pin means and having means actuated by said key controlled means, said legs having keeper means, and means extending from said bolt means for interlocking with said keeper means.
3. In a padlock, a hollow casing having a bearing, a hollow boss within said casing and integral therewith and having a bore, key controlled means rotatably guided by said bearing and having tumbler means for removably interlocking with said bearing, socket means having an opening substantially normal to said bore and in communication therewith, a pair of spaced and hollow nipples extending from said casing and communicating with said bore and the interior of said casing, a spring controlled shackle having a relatively short leg slidably guided by one of said nipples and having a relatively long leg rotatably and slidably guided by the other nipple of said pair, pin means insertable at least in part in said opening and bore and characterizing stop means, bolt means pivotally mounted on said pin means and having means actuated by said key controlled means, said legs having keeper means, means extending from said bolt means for interlocking with said keeper means, and means cooperating with said stop means to limit the linear displacement of said shackle in a direction away from said casing.
4. In a padlock, a hollow casing having a bearing, a hollow boss within said casing and integral therewith and having a bore, key controlled means rotatably guided by said bearing and having tumbler means for removably interlocking with said bearing, socket means integral with said casing and boss and having an opening substantially normal to said bore and in communication therewith, a pair of spaced and hollow nipples extending from said casing, a shackle

having a relatively short leg slidably guided by one of said nipples and having a relatively long leg rotatably and slidably guided by the other nipple of said pair, pin means insertible at least in part in said opening and bore and characterizing stop means overhanging said bore, bolt means pivotally mounted on said pin means and having means adapted to be actuated by said key controlled means, said legs having keeper means, means extending from said bolt means for interlocking with said keeper means, a collar cooperating with said stop means to limit linear displacement of said shackle, and spring means for automatically projecting said shackle in a direction away from said nipples upon disengagement of said bolt means from said keeper means.

5. In a padlock, a hollow casing having a bearing, a hollow boss within said casing and integral therewith and having a bore, key controlled means rotatably guided by said bearing and having tumbler means for removably interlocking with said bearing and including an end having grooved means, a pair of spaced and hollow nipples extending from said casing, a pair of spaced sockets each having an opening and one of said openings being substantially normal to said bore and in communication therewith, a shackle having a relatively short leg slidably guided by one of said nipples and having a relatively long leg rotatably and slidably guided by the other nipple of said pair, a pair of spaced pins at least in part insertible in said openings and one of said pins projecting into said bore to characterize stop means overhanging said bore, spaced bolt means pivotally mounted on said pins and having spaced lower limbs removably interlocked with said grooved means and having spaced upper limbs including laterally extending projections for interlocking with said keeper means, and spring means for urging said limbs towards said legs for interlocking with said keeper means.

6. In a padlock, a hollow casing having a bearing, a hollow boss within said casing and integral therewith and having a bore, key controlled means rotatably guided by said bearing and having spring controlled tumbler means for removably interlocking with said bearing and including a web and having spaced grooves, a pair of spaced and hollow nipples extending from said casing, a pair of spaced sockets each having an opening and one of said openings being substantially normal to said bore and in communication therewith, a shackle having a relatively short leg slidably guided by one of said nipples and having a relatively long leg rotatably and slidably guided by the other nipple of said pair, a pair of spaced pins at least in part insertible in said openings and one of said pins projecting into said bore to characterize stop means overhanging said bore, spaced bolt means pivotally mounted on said pins and having spaced lower limbs removably interlocked with the walls of said grooves and adapted to be actuated by said web and having spaced upper limbs including laterally extending projections for interlocking with said keeper means, and spring means for urging said limbs towards said legs for interlocking with said keeper means.

7. In a padlock, a hollow casing having a bearing, a hollow boss within said casing and integral therewith and having a bore, key controlled means rotatably guided by said bearing and having spring controlled tumbler means for removably interlocking with said bearing and including a web and having spaced grooves, a pair of spaced and hollow nipples extending from said

casing, a pair of spaced sockets each having an opening and one of said openings being substantially normal to said bore and in communication therewith, a shackle having a relatively short leg slidably guided by one of said nipples and having a relatively long leg rotatably and slidably guided by the other nipple of said pair, a pair of spaced pins at least in part insertible in said openings and one of said pins projecting into said bore to characterize stop means overhanging said bore, spaced bolt means pivotally mounted on said pins and having spaced lower limbs removably interlocked with the walls of said grooves and adapted to be actuated by said web and having spaced upper inclined limbs sloping towards the interior of said casing and including laterally extending projections for interlocking with said keeper means, and spring means for urging said limbs towards said legs for interlocking with said keeper means.

8. In a padlock, a hollow casing having a bearing, a hollow boss within said casing and integral therewith and having a bore, key controlled means rotatably guided by said bearing and having tumbler means for removably interlocking with said bearing and including a web and having spaced grooves, a pair of spaced and hollow nipples extending from said casing, a pair of spaced sockets integral with and within said casing and each of said sockets having an opening and one of said openings being substantially normal to said bore and in communication therewith, a U-shaped shackle having a relatively short leg slidably guided by one of said nipples and having a relatively long leg rotatably and slidably guided by the other nipple of said pair, a pair of spaced pins at least in part insertible in said openings and one of said pins projecting into said bore to characterize stop means overhanging said bore, spaced bolt means pivotally mounted on said pins and having spaced lower limbs removably interlocked with the walls of said grooves and straddling and adapted to be actuated by said web and having spaced upper limbs offset relative to said lower limbs and including laterally extending projections for interlocking with said keeper means, and spring means for urging said limbs towards said legs for interlocking with said keeper means.

9. In a padlock, a hollow casing having a bearing, a hollow boss within said casing and integral therewith and having a bore, key controlled means rotatably guided by said bearing and having tumbler means for removably interlocking with said bearing and including a web and having spaced grooves, a pair of spaced and hollow nipples extending from said casing and integral therewith, a pair of spaced sockets integral with and within said casing and each of said sockets having an opening and one of said openings being substantially normal to said bore and in communication therewith, a shackle having a relatively short leg slidably guided by one of said nipples and having a relatively long leg rotatably and slidably guided by the other nipple of said pair, a pair of spaced pins at least in part removably disposed in said openings and one of said pins removably projecting into said bore to characterize stop means overhanging said bore, spaced bolt means pivotally and removably mounted on said pins and having spaced lower limbs removably interlocked with the walls of said grooves and straddling and adapted to be actuated by said web and having spaced upper limbs above said bearing and offset relative to

said lower limbs and including laterally extending projections for disengageably interlocking with said keeper means, and spring means for urging said limbs towards said legs for removably interlocking with said keeper means.

10. In a padlock, a casing having a front wall and a bearing within and integral with said casing and extending rearwardly of said wall and having a slot, said casing having a hollow rim provided with a cutaway portion, a shoulder within said casing and integral with said rim, a cover insertible within said rim and adapted to be seated on said shoulder and including a lip substantially complementary to said cutaway portion, key controlled means rotatably guided in 15 said bearing and including means disengageably interlocked with the walls of said slot, and means extending from said rim to anchor said cover within said rim.

11. In a padlock, a casing having a front wall and a bearing within and integral with said casing and extending rearwardly of said wall and having a slot, said casing having a hollow rim surrounding said bearing and provided with a cutaway portion, a shoulder within said casing 25 and integral with said rim, a cover insertible within said rim and adapted to be seated on said shoulder and including a lip substantially complementary to said cutaway portion to interlock with the walls of the latter, key controlled means rotatably guided in said bearing and including means disengageably interlocked with the walls of said slot, said cover having a recess for rotatably receiving said bearing, bolt means within said casing and actuated by said key controlled means, and a shackle movably associated with

5 said casing and having keeper means for removably interlocking with said bolt means.

12. In a padlock, a casing having a front wall and a bearing within and integral with said casing and extending rearwardly of said wall and having a slot, said casing having a hollow rim surrounding said bearing and provided with a cutaway portion, a shoulder within said casing and integral with said rim, a shackle movably associated with said casing and having keeper means, a cover insertible within said rim and adapted to be seated on said shoulder and including a lip substantially complementary to said cutaway portion and receivable thereby, a key receiving plug rotatably guided by said bearing and having spring controlled means removably interlocking with the walls of said slot, sockets integral with said bearing, pin means projecting from said sockets, and bolt means pivotally sustained by said pin means and actuated by said plug and having means for disengageably interlocking with said keeper means.
